(57) **CLAIM**

The ornamental design for a solar torch light, as shown and described.

DESCRIPTION

FIG. 1 is a perspective view of a solar torch light showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of the solar torch light taken from the circled portion in FIG. 6.

The broken lines showing in the middle portion of the light leg indicates that the appearance of any portion of the article between the break lines forms no part of the claimed design.
